ABSTRACT OF THE DISCLOSURE

A pulse length multiplier circuit produces an output pulse having a length equal to the length of an input pulse multiplied by a multiplication factor which is a function only of the ratio of a charging current and a discharging current. A charging voltage is developed by a pair of charging voltage resistances and is applied across a charging current resistance by one pair of opposite conductivity type emitter-follower transistors to define the charging current. A discharging voltage is developed by a pair of discharging voltage resistances and is applied across a discharging current resistance by another pair of opposite conductivity type emitter-follower transistors to define the discharging current. As a result, the multiplication factor is a function only of the ratio of the charging and discharging current resistances, the ratio of the charging voltage resistances, and the ratio of the discharging voltage resistances.

This invention relates to a pulse length multiplier circuit. More particularly, this invention relates to a circuit for producing an output pulse having a length equal to the length of an input pulse multiplied by a multiplication factor.

According to one aspect of the invention, the multiplication factor is a function only of the ratio of first and second control currents. A first control voltage is developed by a first pair of voltage divider resistances and is applied across a first current limiting resistance to define the first control current. A second control voltage is developed by a second pair of voltage divider resistances and is applied across a second current limiting resistance to define the second control current. Assuming the first and second control voltages are unaltered during application from the respective first and second pairs of voltage divider resistances to the respective first and second current limiting resistances, the multiplication factor is a function only of the ratio of the first and second current limiting resistances, the ratio of the first pair of voltage divider resistances, and the ratio of the second pair of voltage divider resistances. Preferably, the first and second current limiting resistances have like temperature versus resistance characteristics, the first pair of voltage divider resistances have like temperature versus resistance characteristics, and the second pair of voltage divider resistances have like temperature versus resistance characteristics. As a result, the multiplication factor is substantially temperature independent.

In another aspect of the invention, the first control voltage is applied from the first pair of voltage divider resistances across the first charging resistance through a first pair of opposite conductivity type transistors while the second control voltage is applied from the second pair of voltage divider resistances across the second current limiting resistance through a second pair of opposite conductivity type transistors. The first and second pairs of transistors are each connected in a two-stage cascade emitter-follower configuration to provide respective pairs of base-emitter junction voltages having like magnitude and opposite sense. Preferably, the base-emitter junction voltages in the respective first and second pairs of trans-

2

sitors also have like temperature versus voltage characteristics. As a result, the first and second control voltages are unaltered by fluctuations in temperature during application from the respective first and second pairs of voltage divider resistances to the respective first and second current limiting resistances.

These and other aspects and advantages of the invention will become more apparent by reference to the following detailed description of a preferred embodiment when considered in conjunction with the accompanying drawing.

In the drawing:

FIG. 1 is a schematic diagram of a pulse length multiplier circuit incorporating the principles of the invention.

FIG. 2 is a graphic diagram of several waveforms useful in explaining the operation of the pulse length multiplier circuit illustrated in FIG. 1.

Referring to FIGS. 1 and 2, an electrical system includes a high potential line 10 and a low potential line 12 across which a direct current supply voltage V_s is applied by a power source (not shown). The power source may take any convenient form, such as a conventional electrochemical battery.

A pulse length multiplier 14 is connected between an input pulse generator 16 and an output pulse utilized 18. The input pulse generator 16 is connected between the high potential line 10 and the low potential line 12 for developing input pulses P_i each having a period or length T_i defined in response to a given input function. For example, the input pulse generator 16 may be an electronic fuel controller for producing input pulses P_i each having a length T_i determined as a function of at least one operating parameter of an internal combustion engine.

The pulse length multiplier 14 receives the input pulses P_i from the input pulse generator 16, develops an output pulse P_o in response to each input pulse P_i , and applies the output pulses P_o to the output pulse utilized 18. The output pulses P_o each have a period or length T_o , given by the equation

$$(1) \quad T_o = (MF) T_i$$

where MF is a multiplication factor. Thus, the length T_o of the output pulses P_o is equal to the length T_i of the input pulses P_i multiplied by the multiplication factor MF.

The output pulse utilized 18 is connected between the high potential line 10 and the low potential line 12 for performing a given output function in response to the length T_o of the output pulses P_o . For example, the output pulse utilized 18 may be an electronic fuel injector for applying fuel to an internal combustion engine at a constant rate over the length T_o of each of the output pulses P_o .

The pulse length multiplier 14 includes a timing circuit 20 and a toggle circuit 22. The timing circuit 20 includes a timing capacitor 23, a charging circuit 24 and a discharging circuit 26. The timing capacitor 23 is connected between a junction 28 and the low potential line 12 for developing a timing voltage V_t across the capacitor 23 between the junction 28 and the low potential line 12. In a manner which will be more fully described later, the toggle circuit 22 is connected to the junction 28 to nominally maintain the amplitude of the timing voltage V_t substantially constant at a reference level L_r as shown in FIG. 2.

The charging circuit 24 comprises a constant current charging source including a current limiting resistor or charging current resistor 30 and a pair of voltage divider resistors or charging voltage resistors 34 and 36. The resistor 30 is connected between a junction 38 and the high potential line 10. The resistor 34 is connected between a junction 40 and the high potential line 10. The resistor 36 is connected between the junction 40 and the low potential line 12.

Further, the charging circuit 24 includes a pair of emitter-follower transistors 42 and 44 and an amplifier transistor 46. The transistors 42 and 46 are of the NPN junction type while the transistor 44 is of the PNP junction type. The base electrode of the transistor 42 is connected directly to the junction 40. The collector electrode of the transistor 42 is connected directly to the high potential line 10. The emitter electrode of the transistor 42 is connected directly to a junction 48. A biasing resistor 50 is connected between the junction 48 and the low potential line 12. In addition, the base electrode of the transistor 44 is connected directly to the junction 48. The emitter electrode of the transistor 44 and the collector electrode of the transistor 46 are connected directly to the junction 38. The collector electrode of the transistor 44 is connected directly to the base electrode of the transistor 46. The emitter electrode of the transistor 46 is connected directly to the junction 28.

In addition, the charging circuit 24 includes an input transistor 52 of the PNP junction type. An input resistor 54 is connected between an input terminal 56 and the base electrode of the transistor 52. The input terminal 56 is connected directly to the output of the input pulse generator 16. The emitter electrode of the transistor 52 is connected directly to the high potential line 10. The collector electrode of the transistor 52 is connected directly to the junction 40.

The discharging circuit 26 comprises a constant current discharging source including a current limiting resistor or discharging current resistor 58 and a pair of voltage divider resistors or discharging voltage resistors 60 and 62. The resistor 58 is connected between a junction 64 and the low potential line 12. The resistor 60 is connected between a junction 66 and the high potential line 10. The resistor 62 is connected between the junction 66 and the low potential line 12.

Further, the discharging circuit 26 includes a pair of emitter-follower transistors 68 and 70 and an amplifier transistor 72. The transistor 68 is of the PNP junction type while the transistors 70 and 72 are of the NPN junction type. The base electrode of the transistor 68 is connected directly to the junction 66. The emitter electrode of the transistor 68 and the collector electrode of the transistor 72 are connected directly to a junction 74. A biasing resistor 76 is connected between the junction 74 and the high potential line 10. The collector electrode of the transistor 68 is connected directly to the base electrode of the transistor 72. The emitter electrode of the transistor 72 is connected directly to the low potential line 12. The base electrode of the transistor 70 is connected directly to the junction 74. The emitter electrode of the transistor 70 is connected directly to the junction 64. The collector electrode of the transistor 70 is connected directly to the junction 28.

In addition, the discharging circuit 26 includes an input transistor 78 of the NPN junction type. An input resistor 80 is connected between the base electrode of the transistor 78 and the input terminal 56. The emitter electrode of the transistor 78 is connected directly to the low potential line 12. The collector electrode of the transistor 78 is connected directly to the junction 66.

Before proceeding to a description of the operation of the pulse length multiplier circuit 14, a more detailed description of some of the components within the timing circuit 20 is in order. The charging current resistor 30 exhibits a resistance R_{cc} and the discharging current resistor 58 exhibits a resistance R_{dc} where the resistances R_{cc} and R_{dc} have like temperature versus resistance characteristics. The charging voltage resistor 34 exhibits a resistance R_{cv1} and the charging voltage resistor 36 exhibits a resistance R_{cv2} where the resistance R_{cv1} and R_{cv2} have like temperature versus voltage characteristics. The discharging voltage resistor 60 exhibits a resistance R_{dv1} and the discharging voltage resistor 62 exhibits a

resistance R_{dv2} where the resistances R_{dv1} and R_{dv2} have like temperature versus resistance characteristics.

Further, the emitter-follower transistor 42 exhibits a base-emitter junction voltage V_{j1} and the emitter-follower transistor 44 exhibits a base-emitter junction voltage V_{j2} where the junction voltages V_{j1} and V_{j2} have like magnitude and opposite polarity and have like temperature versus voltage characteristics. The emitter-follower transistor 68 exhibits a base-emitter junction voltage V_{j3} and the emitter-follower transistor 70 exhibits a base-emitter junction voltage V_{j4} where the junction voltages V_{j3} and V_{j4} have like magnitude and opposite sense and have like temperature versus voltage characteristics. All of the previously described constraints may be easily met through the proper selection of the various components within the timing circuit 20. Moreover, these constraints tend to be inherent where the timing circuit 20 is fabricated through the use of integrated circuit processing techniques.

Referring to FIGS. 1 and 2, when an input pulse P_1 is initiated at the input terminal 56, the input transistor 78 is rendered fully conductive through the biasing action of the resistor 80. With the transistor 78 turned on, the junction 66 is effectively clamped to the low potential line 12 thereby to render the transistors 68 and 72 fully conductive and the transistor 70 fully nonconductive. With the transistor 70 turned off, discharging of the capacitor 23 is terminated. In addition, when an input pulse P_1 is initiated at the input terminal 56, the input transistor 52 is rendered fully nonconductive through the biasing action of the resistor 54. With the transistor 52 turned off, the junction 40 is effectively unclamped from the high potential line 10 thereby to turn on the transistors 42, 44 and 46 in an emitter-follower configuration. With the transistors 42, 44 and 46 turned on, charging of the capacitor 23 is initiated. The combination of the transistors 44 and 46 acts as a single transistor of the PNP junction type. Thus, when the transistor 44 is turned on, the transistor 46 is also turned on. Conversely, when the transistor 44 is turned off, the transistor 46 is likewise turned off.

With the junction 40 unclamped from the high potential line 10, the charging voltage resistors 34 and 36 are responsive to the supply voltage V_s to develop a charging voltage V_c , given by the equation

$$(2) \quad V_c = \frac{R_{cv1}}{R_{cv1} + R_{cv2}} V_s$$

across the resistor 34 between the junction 40 and the high potential line 10. In response to the charging voltage V_c , the emitter-follower transistors 42 and 44 are turned on through the biasing action of the resistor 50 to apply the charging voltage V_c across the charging current resistor 30 between the junction 38 and the high potential line 10 to develop a charging current I_c , given by the equation

$$(3) \quad I_c = \frac{V_c + (V_{j1} + V_{j2})}{R_{cc}}$$

through the resistor 30. Since the base-emitter junction voltages V_{j1} and V_{j2} have like magnitude and opposite sense, the quantity $(V_{j1} + V_{j2})$ is 0. Moreover, since the base-emitter junction voltages V_{j1} and V_{j2} have like temperature versus voltage characteristics, the quantity $(V_{j1} + V_{j2})$ is 0 regardless of fluctuations in ambient temperature. Consequently, the charging current I_c is given by the equation

$$(4) \quad I_c = \frac{V_c}{R_{cc}}$$

The charging current I_c is applied through the transistor 46 to the junction 28 to charge the timing capacitor 23. As a result, the amplitude of the timing voltage V_t increases from the reference level L_r at a charging rate

determined by the magnitude of the charging current I_c . The amplitude of the timing voltage V_t increases until it reaches a peak level L_p at the termination of the input pulse P_1 . Hence, a charge period T_c is defined between the time when an input pulse P_1 is initiated and the time when the input pulse P_1 is terminated. In other words, the charge period T_c is equal to the length T_1 of the input pulse P_1 . Therefore, the magnitude of the peak level L_p is directly proportional to the length T_1 of the input pulse P_1 .

When an input pulse P_1 is terminated at the input terminal 56, the input transistor 52 is rendered fully conductive through the biasing action of the resistor 54. With the transistor 52 turned on, the junction 40 is effectively clamped to the high potential line 10 thereby to render the transistor 42 fully conductive and the transistors 44 and 46 fully nonconductive. With the transistors 44 and 46 turned off, charging of the capacitor 23 is terminated. In addition, when an input pulse P_1 is terminated at the input terminal 56, the input transistor 78 is rendered fully nonconductive through the biasing action of the resistor 80. With the transistor 78 turned off, the junction 66 is effectively unclamped from the low potential line 12 thereby to turn on the transistors 68, 72 and 74 in an emitter-follower configuration. With the transistors 68, 72 and 74 turned on, discharging of the capacitor 23 is initiated. The combination of the transistors 68 and 72 acts as a single transistor of the PNP junction type. Thus, when the transistor 68 is turned on, the transistor 72 is also turned on.

With the junction 66 unclamped from the low potential line 12, the discharging voltage resistors 60 and 62 are responsive to the supply voltage V_s to develop a discharging voltage V_d , given by the equation

$$(5) \quad V_d = \frac{R_{dv_2}}{R_{dv_1} + R_{dv_2}} V_s$$

across the resistor 62 between the junction 66 and the low potential line 12. In response to the discharging voltage V_d , the emitter-follower transistors 68 and 70 are turned on through the biasing action of the resistor 76 to apply the discharging voltage V_d across the discharging current resistor 58 between the junction 64 and the low potential line 12 to develop a discharging current I_d , given by the equation

$$(6) \quad I_d = \frac{V_d + (V_{j_3} + V_{j_4})}{R_{de}}$$

through the resistor 58. Since the base-emitter junction voltages V_{j_3} and V_{j_4} have like magnitude and opposite sense, the quantity $(V_{j_3} + V_{j_4})$ is 0. Moreover, since the base-emitter junction voltages V_{j_3} and V_{j_4} have like temperature versus voltage characteristics, the quantity $(V_{j_3} + V_{j_4})$ is 0 regardless of fluctuations in ambient temperature. Accordingly, the discharging current I_d is given by the equation

$$(7) \quad I_d = \frac{V_d}{R_{de}}$$

The discharging current I_d is drawn through the transistor 70 from the junction 28 to discharge the timing capacitor 23. As a result, the amplitude of the timing voltage V_t decreases from the peak level L_p at a discharging rate determined by the magnitude of the discharging current I_d . The amplitude of the timing voltage V_t decreases until it reaches the reference level L_r at which it is thereafter maintained. Hence, a discharge period T_d is defined between the time when an input pulse P_1 is terminated and the time when the timing voltage V_t arrives at the reference level L_r . When an input pulse P_1 is again initiated at the input terminal 56, the previously described operating cycle is repeated.

Alternately, the charging current I_c may be applied to the capacitor 23 continually by disconnecting the collector

electrode of the input transistor 52 from the junction 40 thereby to effectively disable the transistor 52. In this event, the operation of the timing circuit 20 is as previously described, provided that the discharging current I_d is greater than the charging current I_c . Conversely, the discharging current I_d may be drawn from the capacitor 23 continually by disconnecting the collector electrode of the input transistor 78 from the junction 66 thereby to effectively disable the transistor 78. In this event, the operation of the timing circuit is as previously described, provided that the charging current I_c is greater than the discharging current I_d .

The toggle circuit 22 performs two distinct functions. First, the toggle circuit 22 nominally maintains the amplitude of the timing voltage V_t substantially constant at the reference level L_r . Second, the toggle circuit 22 produces an output pulse P_o in response to each input pulse P_1 . The output pulses P_o are produced at an output terminal 82 which is connected directly to the input of the output pulse utilized 18. Specifically, the output pulses P_o are each initiated in coincidence with the initial departure of the timing voltage V_t from the reference level L_r and are each terminated in coincidence with the subsequent arrival of the timing voltage V_t at the reference level L_r . Thus, the length T_o of the output pulses P_o is given by the equation

$$(8) \quad T_o = T_c + T_d$$

One embodiment of a toggle circuit for accomplishing the previously described function is illustrated in a copending patent application A-16,677.

Further, as indicated by the Equation 1 the length T_o of the output pulses P_o is equal to the length T_1 of the input pulses P_1 multiplied by a multiplication factor MF. Generally, the multiplication factor MF is given by the equation

$$(9) \quad MF = \frac{I_c}{I_d} + K$$

where K is a constant which is either +1, 0 or -1. In the illustrated embodiment of the pulse length multiplier 14, the constant K is +1.

More particularly, the constant K is +1 where:

- (1) the length T_o of the output pulses P_o is equal to the charge period T_c plus the discharge period T_d ; and
- (2) the charging current I_c is applied to the capacitor 23 only during the charge period T_c while the discharging current I_d is drawn from the capacitor 23 only during discharge period T_d .

The constant K is 0 where:

- (1) the length T_o of the output pulses P_o is equal to the charge period T_c plus the discharge period T_d ; and
- (2) the discharging current I_d is drawn from the capacitor 23 continually while the charging current I_c is applied to the capacitor 23 only during the charge period T_c where the charging current I_c is greater than the discharging current I_d .

Alternately, the constant K is 0 where:

- (1) the length T_o of the output pulses P_o is equal to the discharge period T_d only; and
- (2) the charging current I_c is applied to the capacitor 23 only during the charge period T_c while the discharging current I_d is drawn from the capacitor 23 only during the discharge period T_d .

Lastly, the constant K is -1 where:

- (1) the length T_o of the output pulses P_o is equal to the discharge period T_d only; and
- (2) the discharging current I_d is drawn from the capacitor 23 continually while the charging current I_c is applied to the capacitor 23 only during the charge

period T_e where the charging current I_e is greater than the discharging current I_d .

The simultaneous solution of the Equations 2, 4, 5, 7 and 9 for the multiplication factor MF yields the equation

$$(10) \quad MF = \frac{R_{dc}}{R_{cc}} \left[\frac{1}{1 + \frac{R_{cv_2}}{R_{cv_1}}} \right] \left[1 + \frac{R_{dv_1}}{R_{dv_2}} \right] + K$$

Hence, the multiplication factor MF is a function only of the ratio R_{dc}/R_{cc} of the discharging current resistance R_{dc} to the charging current resistance R_{cc} , the ratio R_{cv_2}/R_{cv_1} of the charging voltage resistance R_{cv_2} to the charging voltage resistance R_{cv_1} , and the ratio R_{dv_1}/R_{dv_2} of the discharging voltage resistance R_{dv_1} to the discharging voltage resistance R_{dv_2} . Further, since the charging current and discharging current resistances R_{cc} and R_{dc} have like temperature versus resistance characteristics, the ratio R_{dc}/R_{cc} remains substantially constant regardless of fluctuations in ambient temperature. Similarly, since the charging voltage resistances R_{cv_1} and R_{cv_2} have like temperature versus resistance characteristics, the ratio R_{cv_2}/R_{cv_1} remains substantially constant regardless of fluctuations in ambient temperature. Likewise, since the discharging voltage resistances R_{dv_1} and R_{dv_2} have like temperature versus resistance characteristics, the ratio R_{dv_1}/R_{dv_2} remains substantially constant regardless of fluctuations in ambient temperature. As a result, the multiplication factor MF is substantially independent of fluctuations in ambient temperature.

It will now be appreciated that the previously described preferred embodiment of the invention is shown for illustrative purposes only. Accordingly, various alterations and modifications may be made to the preferred embodiment without departing from the spirit and scope of the invention.

What is claimed is:

1. For an electrical system providing a supply voltage V_s , a multiplier circuit for extending the length of an input pulse, comprising: means including a capacitance for developing a timing voltage thereacross which is nominally maintained at a reference level; means including a charging current resistance R_{cc} and a discharging current resistance R_{dc} having like temperature versus resistance characteristics; means including a pair of charging voltage resistances R_{cv_1} and R_{cv_2} having like temperature versus resistance characteristics for developing a charging voltage V_c given by the equation

$$(1) \quad V_c = \frac{R_{cv_1}}{R_{cv_1} + R_{cv_2}} V_s$$

means for applying the charging voltage V_c across the charging current resistance R_{cc} to develop a charging current I_e given by the equation

$$(2) \quad I_e = \frac{V_c}{R_{cc}}$$

which is applied to the capacitance in response to the presence of an input pulse; means including a pair of discharging voltage resistances R_{dv_1} and R_{dv_2} having like temperature versus resistance characteristics for developing a discharge voltage V_d given by the equation

$$(3) \quad V_d = \frac{R_{dv_2}}{R_{dv_1} + R_{dv_2}} V_s$$

means for applying the discharging voltage V_d across the discharging current resistance R_{dc} to develop a discharging current I_d given by the equation

$$(4) \quad I_d = \frac{V_d}{R_{dc}}$$

which is drawn from the capacitance in response to the absence of an input pulse; and means for producing an

output pulse having a length defined between the time when the timing voltage initially departs from the reference level until the time when the timing voltage subsequently arrives at the reference level so that the length of the output pulse is equal to the length of the input pulse multiplied by a multiplication factor MF given by the equation

$$(5) \quad MF = \frac{I_e}{I_d} + K$$

where K is a constant, the simultaneous solution of the Equations 1-5 for the multiplication factor MF yielding the equation

$$(6) \quad MF = \frac{R_{dc}}{R_{cc}} \left[\frac{1}{1 + \frac{R_{cv_2}}{R_{cv_1}}} \right] \left[1 + \frac{R_{dv_1}}{R_{dv_2}} \right] + K$$

which indicates that the multiplication factor MF is substantially independent of variations in the various resistances due to fluctuations in ambient temperature.

2. For an electrical system providing a supply voltage V_s , a multiplier circuit for extending the length T_1 of an input pulse P_1 , comprising: means including a capacitor having a capacitance C for developing a timing voltage V_t thereacross which is nominally maintained at a reference level L_r ; means including a charging current resistor and a discharging current resistor having respective resistances R_{cc} and R_{dc} exhibiting like temperature versus resistance characteristics; means including a pair of charging voltage resistors having respective resistances R_{cv_1} and R_{cv_2} exhibiting like temperature versus resistance characteristics for developing a charging voltage V_c given by the equation

$$(1) \quad V_c = \frac{R_{cv_1}}{R_{cv_1} + R_{cv_2}} V_s$$

means including a pair of opposite conductivity type junction transistors interconnected in a cascade emitter-follower configuration to provide respective base-emitter junction voltages V_{j_1} and V_{j_2} having like magnitudes and opposite sense and exhibiting like temperature versus voltage characteristics for applying the charging voltage V_c across the charging current resistance R_{cc} to develop a charging current I_e given by the equation

$$(2) \quad I_e = \frac{V_c + (V_{j_1} + V_{j_2})}{R_{cc}} = \frac{V_c}{R_{cc}}$$

where the quantity $(V_{j_1} + V_{j_2}) = 0$; means for applying the charging current I_e to the capacitance C of the capacitor to increase the timing voltage V_t from the reference level L_r to a peak level L_p in response to the presence of an input pulse P_1 ; means including a pair of discharging voltage resistors having respective resistances R_{dv_1} and R_{dv_2} exhibiting like temperature versus resistance characteristics for developing a discharging voltage V_d given by the equation

$$(3) \quad V_d = \frac{R_{dv_2}}{R_{dv_1} + R_{dv_2}} V_s$$

means including a pair of opposite conductivity type junction transistors interconnected in a cascade emitter-follower configuration to provide respective base-emitter junction voltages V_{j_3} and V_{j_4} having like magnitude and opposite sense and exhibiting like temperature versus voltage characteristics for applying the discharging voltage V_d across the discharging current resistance R_{dc} to develop a discharging current I_d given by the equation

$$(4) \quad I_d = \frac{V_d + (V_{j_3} + V_{j_4})}{R_{dc}} = \frac{V_d}{R_{dc}}$$

where the quantity $(V_{j_3} + V_{j_4}) = 0$; means for drawing the discharging current I_d from the capacitance C of the capacitor to decrease the timing voltage V_t from the peak level

L_p to the reference level L_r in response to the absence of an input pulse P_i ; and means for producing an output pulse P_o having a length T_o defined between the initial departure of the timing voltage V_t from the reference level L_r until the subsequent arrival of the timing voltage V_t at the reference level L_r so that the length T_o of the output pulse P_o is given by the equation

$$(5) \quad T_o = (MF)T_1$$

where MF is a multiplication factor given by the equation

$$(6) \quad MF = \frac{I_e}{I_a} + K$$

where K is a constant which is +1 or -1 or 0, the simultaneous solution of Equations 1-6 for the multiplication factor MF yielding the equation

$$(7) \quad MF = \frac{R_{dc}}{R_{cc}} \left[\frac{1}{1 + \frac{R_{cv_2}}{R_{cv_1}}} \right] \left[1 + \frac{R_{dv_1}}{R_{dv_2}} \right] + K$$

which indicates that the multiplication factor MF is substantially independent of variations in the supply voltage V_s and in the capacitance C as well as independent of variations in the base-emitter junction voltages $V_{j1}-V_{j4}$ and in the resistances R_{cc} , R_{dc} , R_{cv} and R_{dv} due to fluctuations in ambient temperature.

3. A pulse length multiplier circuit, comprising: means including first and second current limiting resistances; means including a first pair of voltage divider resistances having like temperature versus resistance characteristics, the first pair of voltage divider resistances connected to develop a first control voltage which is applied across the first current limiting resistance to define a first control current; means including a second pair of voltage divider resistances having like temperature versus resistance characteristics, the second pair of voltage divider resistances connected to develop a second control voltage which is applied across the second current limiting resistance to define a second control current; means responsive to the first and second control currents for producing an output pulse having a length equal to the length of an input pulse multiplied by a multiplication factor which is a function only of the ratio of the first and second control currents which in turn is a function only of the ratio of the first and second current limiting resistances, the ratio of the first pair of voltage divider resistances and the ratio of the second pair of voltage divider resistances,

whereby the multiplication factor is substantially temperature independent.

4. A pulse length multiplier circuit, comprising: means including first and second current limiting resistances; means including a first pair of voltage divider resistances having like temperature versus resistance characteristics, the first pair of voltage divider resistances connected to develop a first control voltage; means including a first pair of emitter-follower transistors providing respective base-emitter junction voltages having like magnitude and opposite sense and having like temperature versus voltage characteristics, the first pair of emitter-follower transistors connected to apply the first control voltage across the first current limiting resistance to define a first control current; means including a second pair of voltage divider resistances having like temperature versus resistance characteristics, the second pair of voltage divider resistances connected to develop a second control voltage; means including a second pair of emitter-follower transistors providing respective base-emitter junction voltages having like magnitude and opposite sense and having like temperature versus voltage characteristics, the second pair of emitter-follower transistors connected to apply the second control voltage across the second current limiting resistance to define a second control current; and means responsive to the first and second control currents for producing an output pulse having a length equal to the length of an input pulse multiplied by a multiplication factor which is a function only of the ratio of the first and second control currents which in turn is a function only of the ratio of the first and second current limiting resistances, the ratio of the first pair of voltage divider resistances, and the ratio of the second pair of voltage divider resistances, whereby the multiplication factor is substantially temperature independent.
